Attorney.

UNITED STATES PATENT OFFICE.

GEORGE W. WHITEMAN, OF PHILADELPHIA, PENNSYLVANIA.

RAIL JOINT.

Application filed July 14, 1926. Serial No. 122,328.

This invention relates to improvements in splice bars for railroad rail joints.

The object of the invention is to provide a splice bar of novel and efficient construction having parts which may be bent or displaced relatively to other parts thereof in a novel and advantageous manner when the bar is in service to take up the wear which occurs upon the central portions of splice bars forming parts of rail joints at the meeting ends of rail sections.

The invention resides in the novel construction and arrangement of the parts of the bar, whereby, when it is used in a rail joint and its web is bent relatively to its head and its base and is forced inwardly or toward the fishing space, the head or parts of the head of the bar will be forced up into firm engagement with the bottom surfaces of the heads of the meeting end portions of two rail sections at the joint thereof, as will be hereinafter described and claimed.

In the accompanying drawings, illustrating the invention,

Figure 1 is a side view of a rail joint provided with splice bars embodying my invention, the splice bars being shown by full lines and the remaining parts of the joint being shown by dot-and-dash lines.

Figure 2 is a transverse section through the splice bars, on line 2—2 of Fig. 1, the remaining parts of the joint being shown in outline by dot-and-dash lines.

Referring to the drawings, 3, designate the meeting end portions of two rail sections, 4 the oppositely disposed splice bars and 5 the bolts which extend through the rail sections 3 and bars 4 to clamp and secure them together.

Each splice bar 4 is formed of rolled steel and shaped in cross section throughout its length as shown in Fig. 2.

Each bar 4 comprises a head 6, a base 7 and a web 8 connecting the head 6 and base 7.

The head 6 is provided with a rail-engaging surface 9 adapted to bear against the bottom of one side of the rail head 10, and the base 7 is provided with a rail-engaging surface 11 adapted to bear against the top of one side of the rail base 12 when the splice bar is in service.

When herein I speak of "inwardly" I mean in the direction toward the rail, and when herein I speak of "outwardly" I mean

in the reverse direction, when the splice bar is in service.

The head 6 is provided with a longitudinally-extending, outwardly-projecting stiffening portion 13, and the base 7 is provided with a longitudinally-extending, outwardly-projecting stiffening portion or flange 14, the parts 13 and 14 being shaped as clearly shown in the drawings and projecting outwardly beyond a vertical plane extending from the outer surface of the web 8.

The web 8 increases in thickness from the longitudinal central portion thereof toward the head 6 and toward the base 7, and the outer surface of the web 8 is made convex in form, receding from its longitudinal center toward the head 6 and toward the base 7, as illustrated.

The web 8 is of outwardly bowed form, providing the upper portion 15, the axis of whose mass is directed inwardly from the longitudinal central portion of the web to the region of its connection with the head 6, as indicated by the line 16; and providing the lower portion 17 the axis of whose mass is directed inwardly from the longitudinal central portion of the web to the region of its connection with the base 7, as indicated by the line 18.

The longitudinal central portion 19 of the web 8 is weakened by being formed thinner than the remaining portions thereof, the region 20 of the connection of the head 6 with the web 8 is weakened by a longitudinal groove 21 formed in the outer portion of the bar, the region 22 of the connection of the base 7 with the web 8 is weakened by a longitudinal groove 23 formed in the outer portion of the bar, and the central weakened portion 19 is located outwardly of a plane extending through the upper and lower weakened portions 20 and 22, respectively.

It will now be understood that when wear occurs between the bottom of the rail head 10 and the top surfaces of the splice bars 4 in the rail joint, such wear can be compensated for by tightening the bolts 5. When the bolts 5 are tightened, the splice bars will be bent in the regions of their weakened portions 19, 20 and 22, as inward pressure is exerted by the bolts 5 against the longitudinal central portions of the outwardly bowed webs 8, forcing such central portions inwardly and thereby pressing the base portion 7 of the splice bars downwardly and raising the head portions 6

thereof into close engagement with the heads of the rail sections throughout the length of the splice bars.

The extent of the inward displacement of 5 the splice bar webs 8 and the consequent raising of the splice bar heads 6 along the bars will vary in the regions of the respective bolts 5 and will be governed by the extent of wear between the splice bars and the rail 10 sections in such regions, such wear usually increasing toward and being greatest at the central portion of the rail joint, consequently, the bolts 5 nearer the central portion of the rail joint will be tightened to a greater 15 extent than those near the end portions of the joint, causing a greater raising of the central portions of the heads 6 of the splice bars than the end portions of the heads thereof.

20 By constructing and arranging the parts of the bars as shown and described herein, substantially the full area of the rail engaging surface 9 of the head 6 is forced into engagement with the heads of the rail sections 25 with substantially equal pressure throughout the full area of such surface, as the bolts are tightened and the heads 6 of the bars 4 are forced, upwardly, as previously described.

30 I claim as my invention:

1. A splice bar comprising a head, a base, and an outwardly bowed web connecting the head and the base and receding from its longitudinal central portion toward the head 35 and toward the base and constructed to occupy a position outwardly of the fishing space of a rail when the bar is applied thereto.

2. A splice bar comprising a head, a base, 40 and a web connecting the head and the base and constructed to extend outwardly of the fishing space of a rail when the bar is applied thereto and having a convex outer surface which recedes from the longitudinal central portion thereof toward the head and 45 toward the base.

3. A splice bar comprising a head, a base, and a web connecting the head and the base and constructed to extend outwardly of the 50 fishing space of a rail when the bar is applied thereto and having a convex outer surface which recedes from the longitudinal central portion thereof toward the head and toward the base the outer portion of the bar 55 having a longitudinal groove therein in the region of the connection of the web with the head and a longitudinal groove therein in the region of the connection of the web with the base.

60 4. A splice bar comprising a head, a base, and an outwardly bowed web connecting the head and the base and receding and increasing in thickness from the longitudinal central portion thereof toward the head and 65 toward the base.

5. A splice bar comprising a head, a base, and an outwardly bowed web connecting the head and the base and receding from its longitudinal central portion toward the head and toward the base, the outer portion of 70 the bar having a longitudinal groove therein in the region of the connection of the head with the web, and the web increasing in thickness from the longitudinal central portion thereof toward the head and toward 75 the base.

6. A splice bar comprising a head, a base, and an outwardly bowed web connecting the head and the base and receding from its longitudinal central portion toward the head and toward the base, the outer portion of the bar having a longitudinal groove therein in the 80 region of the connection of the base with the web, and the web increasing in thickness from the longitudinal central portion thereof toward the head and toward the base.

7. A splice bar comprising a head, a base, and an outwardly bowed web connecting the head and the base and receding from its longitudinal central portion toward the head and toward the base, the outer portion of the bar having a longitudinal groove therein 90 in the region of the connection of the head with the web, the outer portion of the bar having a longitudinal groove therein in the region of the connection of the base with the web, the web increasing in thickness 100 from the longitudinal central portion thereof toward the head and toward the base, and the head and the base each having a part thereof projecting outwardly beyond a vertical plane extending from the outer 105 surface of the web.

8. A splice bar comprising a head having an upper rail engaging surface, a base having a lower rail engaging surface, and an outwardly bowed web connecting the head and the base, the parts being constructed to cause the head to be forced upwardly when the bar is applied to a rail and the central portion of the web is displaced inwardly and to cause substantially the full area of the rail engaging surface of the head to contact with the rail when the head is forced 115 upwardly.

9. A splice bar comprising a head having an upper rail engaging surface, a base having a lower rail engaging surface, a web connecting the head and the base, the parts being constructed to locate the web outwardly of the fishing space of a rail when the bar is applied thereto and to cause the head to be forced upwardly when the web is bent toward the fishing space and to cause substantially the full area of the rail engaging surface of the head to contact with the rail when the head is forced upwardly.

10. A splice bar comprising a head, a base, and a web connecting the head and the base and having a central weakened portion at the central portion of the web, an upper weakened portion in the region of the connection of the head with the web and a lower weakened portion in the region of the connection of the base with the web, said central weakened portion being outwardly of a plane extending through said upper and lower weakened portions.

In testimony whereof I affix my signature.

GEORGE W. WHITEMAN.
